(57) **CLAIM**

The ornamental design for a LED projection fixture, as shown and described.

DESCRIPTION

FIG. 1 is a back view of an embodiment of an LED projection fixture;

FIG. 2 is a top plan view of the LED projection fixture of FIG. 1;

FIG. 3 is a front perspective view of the LED projection fixture of FIG. 1;

FIG. 4 is a back perspective view of the LED projection fixture of FIG. 1;

FIG. 5 is a back view of a second embodiment of an LED projection fixture;

FIG. 6 is a top plan view of the LED projection fixture of FIG. 5;

FIG. 7 is a front perspective view of the LED projection fixture of FIG. 5;

FIG. 8 is a back perspective view of the LED projection fixture of FIG. 5;

FIG. 9 is a back view of a third embodiment of an LED projection fixture;

FIG. 10 is a top plan view of the LED projection fixture of FIG. 9;

FIG. 11 is a front perspective view of the LED projection fixture of FIG. 9; and,

FIG. 12 is a back perspective view of the LED projection fixture of FIG. 9.

The broken lines shown are included for the purpose of illustrating environmental structure and form no part of the claimed design. None of the broken lines form any part of the claimed design. Patentability is based only on those portions of the article that are shown in solid lines.
